UNITED STATES PATENT OFFICE.

JASON WATERS, OF WEST SUTTON, MASSACHUSETTS.

LADDER.

No. 886,282.

Specification of Letters Patent.

Patented April 28, 1908.

Application filed February 28, 1906. Serial No. 303,403.

To all whom it may concern:

Be it known that, I JASON WATERS, a citizen of the United States, residing at West Sutton, in the county of Worcester and State 5 of Massachusetts, have invented certain new and useful Improvements in Ladders, of which the following is a specification.

The object of this invention is to equalize the bearing of the two sides of a ladder when 10 standing upon rough, slanting or sloping surfaces in an upright position, and to secure as firm a footing as when standing upon a level surface.

A further object of the invention is to provide 15 a ladder with movable and adjustable legs or supporting members, of a simple and improved construction, whereby the ladder may be firmly supported under varying conditions.

With these and other ends in view which will readily appear as the nature of the invention is better understood, the same consists 20 in the improved construction and novel arrangement and combination of parts which 25 will be hereinafter fully described and particularly pointed out in the claims.

In the accompanying drawings has been 30 illustrated a simple and preferred form of the invention; it being, however, understood that no limitation is necessarily made to the precise structural details therein exhibited, 35 but that changes, alterations and modifications within the scope of the invention may be resorted to when desired.

In the drawing, Figure 1 is a front view of 35 the lower portion of a ladder provided with adjustable legs constructed in accordance with the invention, showing the ladder adjusted upon a rocky or uneven surface. Fig. 40 2 is a front view showing the ladder mounted upon a sloping surface. Fig. 3 is an edge view of one of the legs or supporting members. Fig. 4 is a face view of the leg or supporting member as seen from the direction 45 indicated by the arrow X in Fig. 3. Fig. 5 is a face view of the leg or supporting member adjusted to a tilting or sloping position.

Corresponding parts in the several figures are denoted by like characters of reference.

50 A—A designate the side members or uprights and B—B the rungs of a ladder of ordinary construction. The side members A—A are provided near their lower ends with transverse apertures for the passage of bolts whereby the improved legs or supporting members C—C are connected adjustably

with the side members of the ladder; said legs or supporting members being of the improved construction which I will now proceed more fully to describe. Each of said 60 legs or supporting members consists of an elongated plate, made preferably of metal, and provided at its lower end with a foot piece or bracket 10. Said brackets 10 are provided at the ends thereof with depending 65 sharp pointed toes 11 and at their outer edges with likewise depending sharp pointed heel pieces 12, the latter being disposed intermediate the toes, as shown. The said heel piece 12 is disposed to one end of the base 70 member intermediate the toes thereof and spaced from the toes to provide a securing space between them, as indicated by reference numeral 12', the latter mentioned furnishes a means whereby a ladder may be 75 used on joists, elevator beams and similar structures. It is desired to further state that the said heel 12 is offset from the side members or uprights A—A, to extend the bearing of the legs or supporting members 80 C—C when supported on a structure of less width than the distance between the uprights of the ladder, and means are carried between the supporting members C—C, which will be described later on, for driving 85 the heel member into the structure on which it rests, thereby making the ladder permanently secured when supported as above described.

Each of the legs or supporting members 90 C is provided with vertically disposed slots 14—15, the former being formed near the upper ends and the latter near the lower ends of said supporting members; the lower ends of the slots 15 are intersected by transversely disposed segmental slots 16. The slots 14 and 15 are for the passage of the bolts 17 and 21 whereby the legs or supporting members are connected adjustably with the side members of the ladder; said 95 bolts being provided with washers 18 and 22, and with tightening nuts 19 and 23; the latter being shown as a tail nut of ordinary construction. The bolt 17 having the ordinary nut 19 has been shown as carrying a 100 cam member 20 which may be utilized for tightening the bolt so as to secure the leg or supporting member C very firmly in position.

Each of the legs or supporting members C is provided intermediate the slots 14—15 110 with a lateral projection 13 constituting a handle whereby the legs may be conveniently

adjusted when the nuts upon the securing bolts have been loosened; the projections 13 are made quite massive, so that, when the ladder equipped with the supporting members is to be erected upon rocky ground, the said projections may be struck with a hammer or mallet for the purpose of driving the sharp pointed toes into the surface of the ground in order to prevent slipping.

5 The legs or supporting members, as hereinbefore stated, are preferably made of metal, in a substantial and durable manner; the sharp pointed projections 11 and 12 are preferably chilled or otherwise hardened, so that they will readily penetrate into hard soil, or get a firm gripping upon rocky or stony surfaces, or upon pavements of concrete, cement or the like where ordinary ladders are liable to slip. It will be readily seen that the legs or supporting members are capable of vertical adjustment so as to compensate for any inequality in the surface of the soil; in Fig. 1 of the drawings, E represents a rocky or stony surface while in Fig. 5 of the drawings D represents a sloping surface upon which the ladder is erected. The sharp pointed projections 11 will prevent the ladder from slipping outward in either direction, while the intermediate projections 12 will absolutely prevent the ladder from slipping laterally.

As will be seen by reference to Fig. 5 of the drawings, the legs or supporting members may, by engaging the lower bolts 21 with the transverse segmental slots 16, be adjusted in a tilted or inclined position; when the legs or supporting members are adjusted in this position upon a ladder lying prone

upon the ground, and it is desired to erect such ladder, the lowermost members 11 will, 40 when the ladder is erected, engage the ground and hold the ladder firmly while it is being erected, thus greatly facilitating this operation enabling a long and heavy ladder to be erected by a single person without assistance. 45

The improved legs or supporting members constituting the present invention are simple in construction, durable, easily applied to all ladders of ordinary construction, and thoroughly efficient in operation for the purposes for which they are provided. 50

Having thus fully described the invention, what is claimed as new is:—

A ladder having side members provided with transverse bolts, in combination with 55 legs or supporting members comprising elongated plates, said plates being provided with upper and lower vertical slots and engaging the said bolts, transverse arcuate slots intersecting the lower vertical slots, a base member at the lower ends of the elongated plates, projections extending laterally from the legs or supporting members between the upper and lower vertical slots, toes carried by the base and disposed to one side of the legs or 60 supporting members, a heel disposed on one end of the base member and spaced from the toes to provide a securing space between them, said heel being offset from the ladder to extend the bearing portion of the legs or 65 supporting members.

JASON WATERS.
